INTERIOR COLLAR CAN

Filed Jan. 26, 1924

Inventor

John F. Peters

By Murray, Clarke & Carpenter

Atty's.

UNITED STATES PATENT OFFICE

JOHN F. PETERS, OF ROCHESTER, NEW YORK, ASSIGNOR TO AMERICAN CAN COMPANY, OF NEW YORK, N. Y., A CORPORATION OF NEW JERSEY

INTERIOR COLLAR CAN

Application filed January 26, 1924. Serial No. 688,644.

My present invention relates to side tearing strip cans provided with an interior collar extending above the tearing strip to prevent spilling of the contents when the tearing strip is removed and to provide a shoulder adapted to receive the severed cover as a slip closure after the container has been opened.

The principal object of the invention is the provision of improved means of forming the collar band in a container of this character. In accordance with the invention, said collar may be formed by an extremely practical and effective mechanical operation, such as is disclosed in co-pending application of Magnus E. Widell, Serial No. 636,338, assigned to the assignee of the present invention, said operation being very economical since no additional parts or material, other than the collar strip itself, are employed.

Numerous other objects and advantages of the invention will be apparent as it is better understood from the following description, which, taken in connection with the accompanying drawings, discloses a preferred embodiment thereof.

Referring to the drawings,

Figure 1 is an elevational view, partially broken away and shown in section, of a container in which my invention is embodied;

Fig. 2 is a top plan view thereof with the cover removed;

Fig. 3 is an enlarged sectional view of the collar member, taken substantially on the line 3—3 in Fig. 2; and

Fig. 4 is a sectional view of the collar member, taken substantially on the line 4—4 in Fig. 2.

The container as thus illustrated comprises a body 21 having permanently attached top and bottom ends 22 and 23 and being formed with the usual side seam 24. A side tearing strip 20 is set off by parallel score lines 25 and 26 between which are diagonal score lines 27 and 28 adapted to direct the line of tear back to the circumferential lines in case it should be deflected therefrom. A tongue 28 is provided for engagement by a key for removal of the tearing strip.

An internal collar 29 is secured to the body

beneath the tearing strip 20 by means of a bead 31 and extends above said strip to a position near the top of the container. This collar serves to prevent spilling of the contents when the container is opened by removal of the tearing strip and also provides a shoulder adapted to receive the severed cover as a temporary friction closure.

Referring now particularly to Figs. 2 and 3, it will be noted that the ends of the collar 29 are overlapped, as shown at 32, and are riveted together by means of integral rivets 33 formed by perforating the metal of the overlapped ends and turning the displaced metal back upon itself, which operation may be performed by the machine disclosed in co-pending application, Serial No. 636,338, of Magnus E. Widell hereinbefore referred to.

With this form of connection, the ends are tightly secured together without the necessity of employing any special fastening devices and the resultant circular collar is adapted to fit snugly within the container body, presenting a smooth exterior surface since the rivets 33 are formed on the inside of the collar. The mechanical operations involved are relatively simple and, therefore, the construction is economical to a high degree.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A container, comprising a body scored circumferentially to provide a side tearing strip, a top secured to said body, and a collar inserted into and secured to the body in close contact therewith beneath said tearing strip and extending thereabove, said collar having its ends overlapped and perforated with the metal displaced by perforation and forming an inwardly extending rivet

securing said ends together and leaving smooth the exterior of the collar which fits against the interior of the body.

2. A collar for insertion into the body of a tearing strip can, comprising an annular band having its ends overlapped and perforated with the metal displaced by perforation securing said ends together and disposed to form a rivet smooth on the outer surface, the overlapped ends being formed and the rivet construction being made to produce a collar with a smooth outer surface which tightly contacts the inner surface of the can and extends across the tearing strip and maintains substantially the full can height after the tearing strip has been removed in opening the can.

3. A can comprising a body scored circumferentially to provide a side tearing strip, a top secured to an end of said body, and means for rigidifying said body under the tearing strip to hold the strip flat in a vertical direction and in cylindrical form so that it will not yield outward under a tearing pull except along the scores, said rigidifying means consisting of a collar one end of which has an abutting part located in the plane and line of the other end of said collar and preventing said ends from yielding towards each other, the lower end of the collar being rounded inwardly to be forced into the end of the body with a wedging fit and the part of the collar opposite to the tearing strip bearing tightly against said strip, the said forcing of the collar and its bearing against the strip both acting to cause tension of the metal of the body along the scores.

JOHN F. PETERS.
